UNITED STATES PATENT OFFICE.

JOHN GUY AND JOHN PLATT HUYCKE, OF COBOURG, ONTARIO, CANADA.

HAMMER.

1,144,035.

Specification of Letters Patent. Patented June 22, 1915.

Application filed July 6, 1914. Serial No. 349,214.

To all whom it may concern:

Be it known that we, JOHN GUY and JOHN PLATT HUYCKE, both of the town of Cobourg, in the county of Northumberland, in 5 the Province of Ontario, Canada, have invented certain new and useful Improvements in Hammers, of which the following is the specification.

Our invention relates to improvements in 10 hammers and the object of the invention is to devise a hammer which will prevent the stinging effect produced on the hand of the user when the blow is struck and the jar and strain on the hand of the user or on the 15 handle of the hammer, which will insure of an even blow being struck, in which the handle may be easily replaced, and which can be readily changed so as to strike a solid blow when desired, and it consists essentially 20 of a hammer head provided with a longitudinal slot extending from the back to the front of the head and a cross slot leading into the longitudinal slot from each side of the hammer head, a hammer handle fitting 25 between the sides of the longitudinal slot of the head and free of the top and bottom ends of the slot, recesses formed in the hammer handle, cushioning blocks fitting into the recesses and bearing toward the ends of 30 the longitudinal slot of the hammer head, metallic shields fitting over the blocks and a cross pin extending through the hammer handle and secured therein and projecting 35 at its ends into the cross slot formed in the sides of the hammer head.

Figure 1, is a perspective view of a hammer constructed in accordance with our invention. Fig. 2, is a longitudinal section through the head. Fig. 3, is a cross section 40 through the head. Fig. 4, is a perspective view of the hammer handle, cushioning block, retaining pin and metallic shield, separated apart.

In the drawings like letters of reference 45 indicate corresponding parts in each figure.

A is a hammer head of any suitable form provided with a longitudinal slot A' and cross slots A² and A³ leading into the longitudinal slot from the sides of the hammer 50 head.

B is a hammer handle provided with an

end forging B' such end being rectangular in form and of the same horizontal width as the longitudinal slot A' but of less vertical width.

B² are recesses formed in the upper and lower face of a hammer handle.

B³ are resilient blocks fitting within the recesses and provided with covering metallic clips B⁴. When the blocks B³ are inserted in the recess B² and the clips B⁴ placed on the top of the blocks the handle B is inserted in the slot A² so that the clips B³ bear against the ends of the slot.

D is a retaining pin which is driven into 65 the orifice B⁵ extending through the hammer handle so as to project at its ends into the slots A² and A³ as shown particularly in Fig. 3.

From this description it will be readily 70 seen that when a blow is struck the head gives a cushioning blow thereby taking away all jar and strain on the hand of the user and the handle of the hammer preventing the stinging sensation in the hand of the 75 user which is produced when an uneven blow is struck. It will also be seen that in working iron or steel when an unyielding blow is struck the cushion will yield so as to allow of the hammer head to find its own 80 seat and thereby produce an even surface on the work. If desired solid blocks may be substituted for the resilient blocks when it is desired to strike an unyielding blow.

What we claim as our invention is:

1. The combination with the hammer head provided with the usual handle eye and elongated cross slots extending longitudinally of the hammer head and through each side of the hammer head into the eye, of a 90 hammer handle extending into the eye of the head and fitting between the sides of such eye and free of the ends thereof, cushioning means interposed between the hammer handle and the ends of the eye, and a 95 pin projecting from the hammer handle at each side into the cross slots and capable of moving longitudinally thereof in proportion to the yielding of the cushioning means when the hammer blow is struck, as and for 100 the purpose specified.

2. The combination with a hammer head

having the usual eye and hammer handle fitting therein and free of the ends thereof and provided with recesses opposing the ends of the eye, resilient cushions fitting into such recesses and metallic clips extending over the exposed ends of the cushion and bearing against the ends of the eye, and means for preventing the withdrawal of the

handle from the main eye, as and for the purpose specified.

JOHN GUY.

JOHN PLATT HUYCKE.
